UNITED STATES PATENT OFFICE.

EDME THEODORE BRENOT, OF PARIS, FRANCE.

CAUTERIZING APPARATUS.

SPECIFICATION forming part of Letters Patent No. 255,582, dated March 28, 1882.

Application filed March 1, 1882. (No model.) Patented in France February 10, 1881.

To all whom it may concern:

Be it known that I, EDME THEODORE BRENOT, of Paris, in the Republic of France, have invented a certain new and useful Improvement 5 in Cauterizing Apparatus or Thermo-Cauters, of which the following specification is a full description.

This invention relates to cauterizing apparatus in which a suitable cauterizing-iron or 10 hollow metallic tip is heated to the temperature required for cauterization by means of the combustion within itself of carbureted air or similar fuel, and has for its object mainly to furnish a supply of pure air to the said fuel, 15 and to enable the combustion or flame within the tip to be regulated at will by the operator. The air-supply is furnished by a tube separate 20 from that whereby the carbureted air or similar fuel is conveyed, but connected with the same bulb or air-forcing device, so that one movement forces air through both. The two tubes are preferably placed concentric, one inside of the other, so that externally there appears but one tube. The regulation of the 25 combustion or flame is effected by a valve placed in the handle which carries the tip, and capable of being readily controlled by the operator.

The accompanying drawings, which form a 30 part of this specification, represent a cauterizing apparatus constructed in accordance with the invention.

Figure 1 is a view in elevation of such apparatus with a portion of the cauterizing-iron 35 or tip removed, but otherwise complete; Fig. 2, a view in section of the carbureting-vessel and portions of the connected tubes; Fig. 3, a section of the handle and valve apparatus, and Fig. 4 an elevation of the cauterizing-iron or 40 tip and a portion of the handle.

A is an elastic ball with valves, serving to force the air into the regulating-chamber B, and thence through the tube C, carburetor E, tubes H G, and hollow handle I to the cauterizing-iron or tip K. The parts A, B, C, E, and 45 K are or may be of any ordinary or suitable construction. The tubes C G H are connected with the three-branched hollow connection-piece D. The tube C fits over the nipple a,

the tube G over the nipple b, and the tube H 50 over the nipple g. The tube H is of smaller diameter than the tube G, and is inclosed by it, so that an annular space is left between it- 55 self and the inner wall of the tube G. A continuous passage, e, extends through the two lateral branches of the connection-piece D and puts tube H in free communication with tube C. The depending branch, which is inclosed by the stopper of the vessel E, is pierced with an inlet-passage, d, connecting the horizontal passage e with the interior of the said vessel, and an outlet-passage, e, connecting the interior of vessel E through the lateral passage e' with the tube G. The air forced 60 through the tube O by the bulb A passes partly into the vessel E, where it becomes carbureted by the hydrocarbon liquid therein contained, and whence it passes into the tube G and partly into the tube H direct. The opening e'' at the bottom of the depending branch 65 is made small, and an additional orifice, e', is made a short distance above, so that by sliding the connection-piece D in the stopper of vessel E the said lateral orifice may be covered or uncovered and the flow of carbureted air 70 correspondingly diminished or increased. The opening e'' at the bottom of the depending branch 75 is made small, and an additional orifice, e', is made a short distance above, so that by sliding the connection-piece D in the stopper of vessel E the said lateral orifice may be covered or uncovered and the flow of carbureted air correspondingly diminished or increased.

The tubes G H are connected with the handle I, the tube G communicating through the orifices s at the rear or lower end of the handle. A valve, h, regulates the proportionate quantities of carbureted air from the tube G and 80 pure air from the tube H, which pass through the tube l into the cauterizing-iron or tip K, whereon they are ignited. The valve h is attached to a rod, r, sliding in a cross-bar, t, and 85 attached at the opposite end to the disk k, which is itself connected by means of the rods m with a sleeve, n, surrounding the tube l and engaging by an external screw-thread with the thumb-nut O. By turning the nut O in one 90 direction or the other the valve h is raised or lowered across the orifices s, so as to admit into the tube l less or more carbureted air from the tube G. The composition of the gaseous mixture admitted into the tube l is thus controlled, and the combustion within the tip or cauterizing-iron K consequently regulated. Inasmuch as the flow of pure air is checked at 95

the same time that the flow of carbureted air is increased, the apparatus is very sensitive.

A light spring, *j*, is interposed between the cross-bar *t* and a collar on the rod *r*, to facilitate the operation of the valve. The amount of regulation effected by the valve *h* being limited, any inconvenience which might arise from excess of vapor being given off by the carbureting-liquid in the vessel *E* is remedied 10 by sliding the connection in the stopper so as to cover the orifice *e'*.

The part *N* is connected loosely with the handle, so as to turn freely thereon. It is notched, as shown at *N'*, to receive an arm, *P*, 15 fastened to the outer casing of the tip or cauterizing-iron, so that by turning the said part *N* the tip or cauterizing-iron can be unscrewed or the vents be opened or closed without the operator's burning his fingers.

20 Modifications may be made in the details of construction without departing from the spirit of the invention, and parts of the invention can be used without the others. Thus, in place of the thumb-nut *O* for regulating the valve 25 *h*, other equivalent sliding or turning devices could be used.

Having now fully described my said invention and the manner in which the same is or may be carried into effect, what I claim is—

30 1. The combination, with the hollow tubular handle of the cauterizing-iron, of means, as indicated, for controlling the supply of fuel, adapted to be operated by the hand which grasps said handle by means of a thumb-nut or 35 its equivalent, substantially as described.

35 2. The combination, with the cauterizing-iron and its handle, of the two tubes for conveying air and carbureted air or other suitable fuel to the handle, wherein they mix, substantially as described.

40

3. The combination, with the carbureting-vessel and stopper, of the connection-piece having inlet and outlet passages and two or more openings into the outlet-passage, and adapted to be moved in and out, so as to cover 45 or uncover one or more of said openings, and thus regulate the flow of the carbureted air, substantially as described.

4. The combination of the air-forcing bulb, the carburetor, the hollow handle, the tube 50 leading from the air-forcing bulb to the carburetor, the two tubes leading from the latter to the hollow handle, and the valve apparatus connected with said handle, substantially as described.

5. The combination, with the cauterizing-iron, its sheath and handle, of a movable piece adapted to engage the said iron and its sheath, so that they can be turned without burning the operator's fingers, substantially as described. 60

6. The combination, with the handle and its valve apparatus, of the carburetor, the movable connection-piece, with inlet and outlet passages, and two or more openings into the outlet-passage, and the two tubes connecting the 65 handle with said connection-piece, substantially as described.

7. The combination, with the handle and its valve apparatus, of the two concentric tubes, one inside the other, for conveying air and carbureted air or other gaseous fuel into said handle, substantially as described. 70

In testimony whereof I have hereunto signed this specification in presence of two subscribing witnesses.

EDME THEODORE BRENOT.
